CLAIM

The ornamental design for a wrist band, as shown and described.

DESCRIPTION

FIG. 1 is a perspective view of a wrist band showing my new design;

FIG. 2 is a front view thereof;

FIG. 3 is a back view thereof;

FIG. 4 is a first side view thereof;

FIG. 5 is an opposite second side view thereof;

FIG. 6 is a top plan view, with the bottom plan view being a mirror image thereof; and,

FIG. 7 is a perspective view thereof, shown in a configuration of use.

The even-length broken lines are directed to environment, represent unclaimed subject matter, and form no part of the claimed design. In FIG. 7, the even-length broken lines showing a human hand and arm is for illustrative purposes only and forms no part of the claimed design.

1 Claim, 5 Drawing Sheets
